UNITED STATES PATENT OFFICE.

ISAIAH IVERSON DAVIS, JR., OF CONCORD, NORTH CAROLINA.

LABEL-GUMMING DEVICE.

1,261,217.

Specification of Letters Patent. Patented Apr. 2, 1918.

Application filed July 27, 1915. Serial No. 42,145.

To all whom it may concern:

Be it known that I, ISAIAH I. DAVIS, Jr., a citizen of the United States, residing at Concord, in the county of Cabarrus and 5 State of North Carolina, have invented new and useful Improvements in Label-Gumming Devices, of which the following is a specification.

The invention hereinafter described and 10 claimed, and illustrated in the drawings herewith, relates to a machine for gumming labels.

It has for its object to provide a simple and convenient device for those dealers (particularly druggists) who are accustomed to 15 apply labels, address slips, and the like, to articles sold by them, by means of which they can quickly and effectively gum labels for application to the goods.

20 While I show and describe a manually-operated device, it will be understood that I do not limit myself to this, as the device may, of course, be power-operated, and still be within the scope of my invention.

25 In the drawings herewith,

Figure 1 is a view in front elevation of the machine.

Fig. 2 is a view in plan of the front portion of the machine.

30 Fig. 3 is a view in side elevation of the machine in position for use, portions thereof being in section.

Fig. 4 is a detail view in side elevation of the gum roll carrier.

35 Fig. 5 is a detail view in front elevation of a portion of the gum roll, to show its bearing and driving means.

Fig. 6 is a detail view in side elevation of the delivery table or rack.

40 Fig. 7 is a view of the machine in side elevation showing the machine in storage or non-usable position.

Referring to the drawings by numerals, like numbers indicating like parts in the 45 several views, 10 designates the adhesive tank or container which is of generally rectangular shape and formed of any suitable material, preferably metal.

The said tank 10 has a flat bottom 11, in 50 order that, as shown in Fig. 7, it may be stood upright when not in use and the adhesive, which will flow to the bottom thereof, conserved. The said tank may, if desired, be provided with fastening lugs 10^a as 55 shown in Fig. 1, by which it may be secured to a counter or bench, these lugs being

shown as open at one side so that they may be slipped into engagement with suitable screws or fastening means.

The general contour and outline of the 60 container or tank 10 is rectangular, as stated, but one of its walls 11 is extended, and upwardly curved at 12, so as to form, with the side walls 13, a well 14 as shown in Fig. 3.

The opposed wall 15 of the container, is, 65 through a portion 16, of its length inclined, as shown, to form a chute or label runway, down which the labels will slide to the adhesive applying instrumentalities now to be described, the chute having on each side 70 standing flanges or wings 17 to prevent the label leaving the runway as it slides down.

Said side walls 13 extend somewhat beyond the container proper, and an end partition 18, preferably curved to conform to the 75 gum roll, stops communication between the container and well 14, except for the feed slot 19 in the end partition, which, when the device is in the operative position shown in Fig. 3, permits the adhesive to flow to the 80 well 14 formed by the extended and upwardly curved wall 11, hereinbefore referred to, in sufficient quantity, the bulk remaining in the container or tank and feeding out at intervals on the principle of the well-known 85 self-feeding ink wells, and the like.

Said extended side walls 13 form supports for the adhesive-applying instrumentalities, which comprises a frame made up of the side plates 20, having clips 21 which 90 engage the extended side walls 13; said side plates 20 being coupled by the transverse bar 22, which gives a rigid frame and serves as a handy means by which it may be lifted out or placed in position. Said side plates 95 20 are provided with the bearings 23, which, as herein shown are of the open type and adapted to receive the gudgeons 24 of a gum roll 25 of such dimensions, that, when mounted in the bearings 23, said roll will dip in 100 the adhesive of the well 14 formed by the extended curved wall and the side walls of the tank, hereinbefore described.

Mounted in open bearings formed in the side plates 20 just above the gum roll 25 is 105 a gripper element 26, shown in the present instance in the form of star wheels spaced from one another and touching with their points the gum roll 25, springs 27 being provided at each end of the gripper element to 110 hold it always in place in the bearings and in light gripping contact with the roll, so

that it will be rotated by contact with the roll or a label, as the said gum roll 25 is rotated.

A convenient means for rotating the gum roll 25 is by means of the turn button or knurled head 28, which is provided with a threaded shank 29 and is intended to be screwed into one end of the gum roll 25 through a suitable aperture in the side plate 20. Said turn button 28 serves not only as a means for driving the roller, but also locks it and the frame formed by the side plates 20 and bar 21 in place so as to prevent accidental displacement thereof. By simply unscrewing the turn button, the frame may be removed to permit refilling of the tank 10, and both roll 25 and gripper 26 disassembled for the purpose of cleaning.

It will be seen on reference to Fig. 3 that 20 that chute or runway formed by the sloping wall 16 delivers to the bite of the roll 25 and gripper 26, so that a label dropped face upward on the runway will slide into the bite of the roll and gripper and be gummed on 25 its underside as the roll 25 is operated to drive the label through. The star wheels of the gripper 26 touch the label and gum roll only at separated points, and all danger of smearing the gripper with gum and soiling 30 the face of labels is eliminated.

On the delivery side of the roll 25 and gripper 26 is a pick-off table for the gummed labels, said table being formed preferably of a clip 30 which is removably mounted on the 35 end of the upwardly curved wall 12 and has extending therefrom a curved wall 31 which extends rearwardly to the roll 25 forming a shield to close the well 14 against dirt and the like. Secured to said shield 31 are fingers 32 of light spring wire which curve rearwardly and upwardly from the clip 30 and then continue straight to the gum roll on which they rest with slight spring pressure, said roll being preferably grooved at 40 45 33 to form seats for the ends of the fingers.

This construction gives an open table or rack to which the gummed labels are delivered and from which they may be readily removed, the open rack permitting the ready 50 grasping of such labels, and the rearwardly and upwardly curving fingers give a clearance space for the fingers in removing a gummed label from the table.

The device may, as shown in Fig. 7, be 55 stood on end when not in use, allowing the adhesive to drain back out of the well into the body of the tank, and the curved wall 12 will to some extent cover and protect the gumming instrumentalities from dust and 60 dirt.

The present embodiment shows a manually-operated device of small size for desk or counter use, but it will be obvious that the construction may be of such dimensions as to 65 demand power-driven gumming mechanism,

in which event, suitable driving means would be coupled to the roll 25 to give a continuous drive.

It will be seen that I have provided a machine in which labels may be very conveniently and expeditiously gummed, and one in which a supply of adhesive is kept without deterioration for a long time owing to the fact that it is not exposed to the air and is protected at its delivery point to the gum roll, that it will not become contaminated by dirt or foreign particles. Furthermore, the construction is such that the gumming instrumentalities may be quickly removed for replenishing of the tank and readily disassembled for cleaning, the construction being such that no mechanical skill is necessary to assemble and disassemble the parts.

It is obvious that changes in structure may be made and mechanical expeditencies other than those disclosed adopted in working out my invention without departing from the principles thereof.

I claim:

1. In a device of the class described, and in combination, a container having an open well at one end in communication with said container, a gum roll mounted in said well, a gripper member in operative relation to said roll, a removable shield for said well and gum roll fitting into the well, means for holding the removable shield in the well, and a label receiving means carried by said shield.

2. In a device of the class described, and in combination, a container having an open well at one end in communication with said container, a gum roll mounted in said well, a gripper member in operative relation to said roll, a rearwardly curved shield closing the front of the well and partly housing said gum roll, and a label receiving table comprising a plurality of spaced-apart fingers having a forwardly extending horizontal receiving section and a rearwardly curved front section to permit ready removal of the labels therefrom, said fingers being connected to said shield at the lower ends of their rearwardly curved front sections.

3. In a device of the class described, and in combination, a container having an open well at one end communicating with said container, a gum roll mounted in said well, a gripper member in operative relation to said roll, a label-receiving table formed of spaced apart fingers having horizontal portions resting on the gum roll and rearwardly curved portions, and a removable shield closing the front of the well and to which said fingers are secured.

4. In a device of the class described, and in combination, a container having an open well at one end in communication with said container, removable gumming mechanism

mounted in said well and comprising side plates, a rigid connection between said plates, a gum roll mounted in open bearings in said side plates, a gripper member mounted in open bearings in said side plates in operative relation to said gum roll, and roll operating means extending exteriorly of the well and serving to lock said gumming mechanism in place.

5 5. In a device of the class described, and in combination, a container having an open well at one end in communication with said container, a removable frame comprising side plates having clips adapted to engage the sides of said well, a transverse bar for coupling said side plates, bearings in said side plates, a gum-roll mounted in said bearings, a gripper mechanism mounted in bearings in said side plates in operative relation to said roll, and a pick-off table for receiving the labels from said roll.

10

15

20

6. In a device of the class described, and in combination, a container having an open well at one end in communication with said container, a removable gumming mechanism 25 in said well and comprising side plates, a rigid connection between said plates, a roll mounted in said side plates, a gripper mechanism in operative relation to said roll, a shield closing the front wall of the well and partly housing said gum roll, and a table comprising spaced-apart fingers engaging said roll at one end and secured at their other ends to said shield.

30

In testimony whereof I have hereunto set 35 my hand in presence of two subscribing witnesses.
